A. L. FEILD

METHOD OF WORKING OPEN HEARTH FURNACES AND THE LIKE

Filed April 29, 1924

UNITED STATES PATENT OFFICE.

ALEXANDER L. FEILD, OF JACKSON HEIGHTS, NEW YORK, ASSIGNOR TO THE LINDE AIR PRODUCTS COMPANY, A CORPORATION OF OHIO.

METHOD OF WORKING OPEN-HEARTH FURNACES AND THE LIKE.

Application filed April 29, 1924. Serial No. 709,900.

To all whom it may concern:

Be it known that I, ALEXANDER L. FEILD, a citizen of the United States, residing at Jackson Heights, in the county of Queens 5 and State of New York, have invented certain new and useful Improvements in Methods of Working Open-Hearth Furnaces and the like, of which the following is a specification.

- 10 This invention relates to furnacing operations conducted at high temperatures, and comprises the utilization of a gas current within the furnace to shield portions of its wall liable to failure from excessive heating.
- 15 The invention is particularly applicable to metallurgical furnaces of the open-hearth or Siemens-Martin type. Reference will therefore be made principally to this use, but it is to be understood that the invention 20 may be advantageously applied in other high temperature operations.

It has long been realized that the open hearth process could be operated much more efficiently by increasing the temperature of 25 the flame playing upon the charge. Increase of temperature may readily be obtained by supplying oxygen or oxygen-enriched air, instead of atmospheric air. In practice, however, such processes are precluded, 30 cause there is no available refractory which can sustain the heat so generated.

The roof of the furnace is subjected to the severest conditions. Silica brick, the best available refractory at the present time, is 35 heated almost to the point of failure by the combustion in the furnace of the gas and atmospheric air now customarily supplied. Using good producer gas and air (about 40% excess), both preheated in the regenerators to around 1000° C., the maximum combustion temperature will generally approximate 2100° C. Although the flame is directed toward the bottom of the furnace, the temperature of the roof always 40 exceeds that of the fused charge or bath, due to the high capacity of the latter for absorbing heat. Thus when the temperature of the bath is 1600° C., that of the roof will ordinarily be 1700° C. or more. Silica 45 brick will not stand a higher temperature.

This condition results in other serious disadvantages besides that of preventing increase of combustion temperature in the furnace. There is, for example, a very great

loss of heat by radiation from the roof. It is 55 impractical to prevent this by insulation, because the retained heat would be destructive.

I have discovered that these difficulties may be avoided by passing a current of a suitable gas along the under side of the 60 roof. This gas should be preheated, or should be combustible in part, or both, in order that the effective temperature of the furnace may not be materially lowered. Various gases or gaseous mixtures may be 65 used. A particularly advantageous procedure is to work the open hearth process, according to the present invention, with atmospheric air treated to produce two fractions containing respectively a greater and a 70 less proportion of oxygen than exists in air. Both these fractions will preferably be preheated by passing through regenerators containing the usual checkerwork or the like.

The high oxygen fraction is used with producer gas, oil, or other suitable combustible to produce a bath temperature hitherto considered to have a disastrous effect upon the furnace roof and checkerwork. The low oxygen fraction is passed in a stream below the 75 roof, and being at a considerably lower temperature than the bath or the high temperature flame at the surface of the bath, it abstracts heat from the roof and carries it off, thereby limiting the temperature which the 80 roof can attain. At the exit ports the two gas streams unite, so that the temperature to which the checkerwork is subjected is 85 kept within practical bounds.

The low-oxygen fraction will ordinarily 90 be supplied together with a combustible gas, oil, or the like, so that heat will be generated by the protective gas current sweeping the roof. However, the term "low-oxygen" 95 includes gases containing little or no oxygen. When such gases are used, the preheating should be adequate to prevent an objectionable reduction of the furnace temperature.

Illustrative embodiments of the invention are illustrated in the accompanying drawing, in which—

Fig. 1 is a somewhat diagrammatic vertical section through half of an open hearth furnace and its regenerators;

Fig. 2 is a section on line II—II of Fig. 105 1; and

Fig. 3 is a diagram of a modified port arrangement.

In Figs. 1 and 2 of the drawing, reference numeral 1 denotes a furnace of conventional type having a hearth 2 and regenerators 3, 4, and 5, suitably connected with the gas and air supply, not shown. As noted on Fig. 1, the regenerators are adapted to serve respectively for the preheating of fuel gas, low-oxygen gas, and air or oxygenated air. Uptakes 6 and 7 conduct the comburent 10 gases from regenerators 4 and 5 to inlet ports 8 and 9, respectively. These ports are directed so as to send one gas stream toward the bath and another toward the roof. The fuel gas is fed into the furnace from regenerator 15 3 by uptakes (not shown) leading to ports 10 and 11, 12 and 13 (Fig. 2). It will be understood that these ports are directed as are their corresponding ports 8 and 9.

The relative amounts of fuel gas and comburent may be adjusted by suitably proportioning the cross-sectional area of the uptakes. Figs. 1 and 2 of the drawing illustrate one practical embodiment, but the invention is not limited to the arrangement 25 or proportions shown. Special conditions may necessitate a marked increase or decrease in capacity of one or more of the inlets to the furnace.

In Fig. 3 an alternative arrangement of 30 ports is shown. In this, the fuel gas is fed through a central passage 14 divided by a partition 15 which is flared at the end adjacent to the furnace so that one portion of the gas stream is deflected upwardly and 35 the other downwardly. The comburent gases (preferably oxygenated air and air containing an increased proportion of nitrogen) are fed respectively through passages 17 and 16.

40 The flow of gases will be reversed in the usual manner, entering from the opposite end of the furnace, which is identical with that illustrated. If necessary, suitable dampers may be provided to secure a proper 45 distribution of the furnace gases to the three regenerators.

It will be apparent that in both forms of furnace illustrated, the low-oxygen gas and its combustible sweep the under side of the 50 furnace roof, thus protecting it from the materially higher temperatures prevailing in the lower part of the furnace. The oxygen content of the air fractions may be adjusted as desired, provided the maximum 55 heat of combustion produced by the low-oxygen gas is substantially less than that which would cause failure of the roof. Since the "cooling" gas introduces a large amount of heat, either as sensible heat, or 60 heat of reaction, or both, the furnace processes are not interfered with.

Air separated into two fractions containing respectively 30% and 18% of oxygen by weight may be advantageously used. Various other proportions are also suitable.

The gases used in the process may be prepared in any desired way, but the fractionation of air affords a cheap and convenient source.

Important improvements in the open 70 hearth process and other high temperature operations are produced by the use of a protective gas in accordance with the present invention. Among these improvements may be mentioned the reduction of the time 75 for reaction, utilization of low grade fuel gas, and the oxidation of materials not readily worked with the present flame of relatively low oxidizing power.

The present process may be used, with or 80 without modification, in a number of connections other than those specifically described herein, and the invention is therefore defined broadly in the appended claims.

I claim:

1. Process of conducting high temperature furnacing operations, comprising passing a hot gas, of lower temperature than the main reaction zone of the furnace, between such zone and a portion of the furnace liable to failure from excessive heating.

2. Process of conducting high temperature furnacing operations, comprising passing a combustible gas and a gas containing oxygen in lower proportion than that in atmospheric air, between such zone and a portion of the furnace liable to failure from excessive heating.

3. Process of conducting high temperature furnacing operations, comprising generating a high temperature in the reaction zone of the furnace, and passing a hot gas of relatively lower temperature along the inner surface of the roof of such zone.

4. Process of conducting high temperature furnacing operations, comprising passing a gas containing a higher proportion of oxygen than atmospheric air into the reaction zone of the furnace to produce a temperature therein which would normally be destructive to a portion of the furnace wall, and protecting such portion by causing a hot gas of relatively lower temperature to sweep over its inner surface.

5. Process of working furnaces of the open-hearth type, comprising utilizing a gas rich in oxygen to produce a hearth temperature in excess of that obtainable by combustion involving air, and preventing the adverse effects of heat upon the furnace roof by passing a hot gas of lower temperature in contact with the inner surface of the roof.

6. Process of working furnaces of the open-hearth type, comprising utilizing a gas rich in oxygen to produce a hearth temperature in excess of that obtainable by combustion involving air, and preventing the adverse effects of heat upon the furnace roof by

passing a fuel gas in admixture with a low-oxygen gas in contact with the inner surface of the roof.

7. Process of working furnaces of the open-hearth type, comprising heating the bath by burning a fuel gas with a gas containing oxygen in greater proportion than that in atmospheric air, and passing in contact

with the inner surface of the furnace roof, a preheated combustible gas and a pre-heated low-oxygen gas, whereby the roof is shielded from the destructive action of heat from the bath. 10

In testimony whereof, I affix by signature.

ALEXANDER L. FEILD.
